United States Patent Office.

L. A. POWERS, OF MERIDEN, CONNECTICUT.

Letters Patent No. 80,009, dated July 14, 1868.

IMPROVEMENT IN TABLE-FORKS.

The Schedule referred to in these Letters Patent and making part of the same.

TO ALL WHOM IT MAY CONCERN:

Be it known that I, L. A. POWERS, of Meriden, in the county of New Haven, in the State of Connecticut, have invented a new and useful Improvement in Carving-Forks; and I do hereby declare the following to be a full, clear, and exact description thereof, which will enable those skilled in the art to make and use the same, reference being had to the accompanying drawing, forming part of this specification, in which drawing—

Figure 1 represents a sectional side elevation of this invention.

Figure 2 is a plan or top view thereof.

Similar letters indicate corresponding parts.

This invention consists in a socket for the guard of a carving-fork, cast or otherwise made solid with the bolster, but independent of the fork, and attached to the tang of said fork by rivets or otherwise, in such a manner that the process of producing the fork is materially simplified, and that a durable and handsome article can be furnished at a comparatively low price.

A represents my fork, which is secured in the handle, B, by rivets, or any other suitable means.

C is the bolster, which I produce by casting it from any suitable alloy, or in any other desirable manner, either in two halves, as shown in the drawing, if the fork is provided with a scale-tang, or in one solid piece, if the shape of the tang is such that a solid bolster can be conveniently used.

Together with the bolster, or with one-half thereof, I form the socket D, for the guard E, in such a manner that said socket is made solid with the bolster, either by casting them together, or by swaging or other means. By making the bolster and the socket independent of the fork itself, I am enabled to produce said fork with much less labor and expense than if the socket is made solid with the fork, as usual, and after the bolster and socket have been cast or otherwise produced in the required shape, I secure the same to the tang of the fork by rivets or otherwise.

This invention is applicable particularly to forks of that class for which a patent was granted to James D. Frary, April 21, 1868, which forks are produced by stamping them out of sheet steel; and by making the bolster and socket solid and independent of the fork, I am enabled to produce a carving-fork, with a guard, at a comparatively small increase of the price over an ordinary fork; and a fork provided with my bolster and socket is just as durable as a carving-fork of the ordinary kind having its socket made solid with the tang of the fork.

Having thus described my invention, what I claim as new, and desire to secure by Letters Patent, is—

Making the socket for the guard of a carving-fork solid with the bolster, or with a portion of said bolster, and independent of the tang or body of the fork, substantially as and for the purpose set forth.
